[57] **CLAIM**

The ornamental design for a bottle or similar article, as shown and described.

DESCRIPTION

FIG. 1 is a front elevation view of a bottle or similar article embodying my new design;
FIG. 2 is a top view thereof;
FIG. 3 is a rear elevation view thereof;
FIG. 4 is a bottom view thereof;

FIG. 5 is a side elevation view thereof, the opposite side thereof being a mirror image;
FIG. 6 is a front perspective view thereof;
FIG. 7 is a front elevation view of a container embodying a second embodiment of my new design;
FIG. 8 is a top view of the embodiment of FIG. 7;
FIG. 9 is a rear elevation view of the embodiment of FIG. 7;
FIG. 10 is a bottom view of the embodiment of FIG. 7;
FIG. 11 is a side elevation view of the embodiment of FIG. 7, the opposite side thereof being a mirror image;
FIG. 12 is a front perspective view of the embodiment of FIG. 7;
FIG. 13 is a front elevation view of a container embodying a third embodiment of my new design;
FIG. 14 is a top view of the embodiment of FIG. 13;
FIG. 15 is a rear elevation view of the embodiment of FIG. 13;
FIG. 16 is a bottom view of the embodiment of FIG. 13;
FIG. 17 is a side elevation view of the embodiment of FIG. 13, the opposite side thereof being a mirror image;
FIG. 18 is a front perspective view of the embodiment of FIG. 13;
FIG. 19 is a front elevation view of a container embodying a fourth embodiment of my new design;
FIG. 20 is a top view of the embodiment of FIG. 19;
FIG. 21 is a rear elevation view of the embodiment of FIG. 19;
FIG. 22 is a bottom view of the embodiment of FIG. 19;
FIG. 23 is a side elevation top view of the embodiment of FIG. 19, the opposite side thereof being a mirror image; and
FIG. 24 is a front perspective view of the embodiment of FIG. 19.
